UNITED STATES PATENT OFFICE.

WILLIAM F. BOSSERT, OF UTICA, NEW YORK.

INSULATED RAIL-JOINT.

No. 833,020.

Specification of Letters Patent.

Patented Oct. 9, 1906.

Application filed January 11, 1906. Serial No. 295,584.

To all whom it may concern:

Be it known that I, WILLIAM F. BOSSERT, a citizen of the United States, residing at Utica, in the county of Oneida and State of New York, have invented certain new and useful Improvements in Insulated Rail-Joints, of which the following is a specification, reference being had therein to the accompanying drawings.

10 This invention relates to means for insulating railway-rails from the metallic fish-plates or chairs on which they rest and also the provision of means for insulating the contiguous ends of the rails from one another 15 where they rest in a common chair or support.

15 The special object of the invention is to provide for the insulation of rails by a durable and effective device combining strength 20 with simplicity of parts and providing means whereby a portion of the insulating material, especially the parts at the ends of the rails, which, owing to their bearing-surfaces and the heavy strain to which they are subjected 25 by the pounding action of wheels passing over them, are quite likely to become defective and form a short circuit from one rail to another or continuous rail and may be readily replaced without disturbing the joint or rails 30 in any way.

30 My invention relates, further, in the construction of a device of this nature which will securely hold the rails against any lateral movement when in alignment with each 35 other, while the insulating material is firmly held in position around the rail.

35 My invention consists, further, in the provision of such an insulation of the contacting faces of different elements of the rail-joint accom- 40 modating itself to the usual contractions and expansions without disturbing the insulated character of the joint, and to this end the invention provides not only a complete insulation for the base, web, and contiguous 45 ends of the rail, but also for the bolts and different parts connected therewith.

45 My invention consists, further, in the provision of means whereby greater durability may be secured to the insulated rail-joint and 50 more security to the railway-track than the ordinary insulation in use, thereby prolonging the effective lifetime of the insulating material used, as the parts of the insulation liable to disintegration and destruction of 55 other parts may be easily replaced, while the remaining parts of the insulating material or

the joint itself may not be disturbed, thereby reducing the cost of construction and maintenance of the line.

My invention is illustrated in the accompanying drawings, in which—

Figure 1 is a perspective view of my improved rail-joint, showing the insulation between the rails and between the various parts. Fig. 2 is a cross-sectional view through Fig. 6. Fig. 3 is a perspective view of a slight modification in the construction, showing two half-cylindrical pieces of insulation under the tread of the rail in place of the form shown in Fig. 1. Fig. 4 is a cross-sectional view of Fig. 3. Fig. 5 is a sectional view showing a slight modification. Fig. 6 is a perspective view of a still further modification of the construction of the invention, showing one of the web-sections of the plates 75 as integral with the bottom portion. Fig. 7 is a cross-sectional view through Fig. 6, and Fig. 8 is a sectional view of a slight modification. Fig. 9 is a detailed view of a slight modification of my invention.

Reference now being had to the details of the drawings by numerals, 1 designates the railway-tie upon which the rails are adapted to be held in any suitable manner. Each rail has a tread portion 2, web 3, and a base 85 4, and said web portion is provided with a series of apertures to receive the bolts 5.

Referring to Figs. 1 and 2 of the drawings, I have shown a rail-chair 6, made of a single piece of metal, which surrounds the base of the rail and which has two upright portions positioned on either side of the webs of the rails with slight spaces intervening between. Said upright portions are provided with apertures adapted to register with the apertures 95 formed in the webs of the rails and through which the bolts 5 pass. Wooden strips 7, having apertures to receive the bolts 5 and capable of slight resiliency to permit of tight clamping of same upon the web portions of the rails and still allow sufficiently for expansions and contractions of the rails are placed in the spaces intermediate the upright web portions of the chair and web portions of the rails. A suitable insulation 8 is placed upon the upper surface of the bottom of the chair 105 and upon which the bases of the rails rest, and insulating strips 9 are placed upon the upper inclined surfaces of the flanges of the bases of the rails to thoroughly insulate the 110 same from the chair. The bolts which hold the parts together are mounted in flanged

insulation-sleeves 10, the flanges of which bear against the outer faces of the upright portions of the chair, and suitable tightening-nuts 11 are fitted to the threaded ends of the bolts, 5 while washers 12 are interposed between the nuts and the sleeves and also between the heads of the bolts and adjacent insulation-sleeves. In the construction shown in Figs. 1 and 2 of the drawings the upper ends of the 10 webs of the chair are inclined in planes substantially at right angles to each other and form supports for the replaceable insulation-strips 13, the upper and inner faces of which insulation-strips are adapted to contact, respectively, with the under surfaces of the treads of the rails and the opposite faces of the webs of the rails. It will be noted that the contact-surfaces of said insulation-strips conform to the inclined ends of the web portions of the chair, and when the nuts upon the 20 bolts are tightened a wedging action is effected intermediate the chair ends and the insulation-strips 13 whereby the latter may be clamped securely against the rails.

25 In Figs. 3 to 5, inclusive, I have shown the upper ends of the web portions of the chair as cupped longitudinally to receive the insulation-strips 14, which are preferably convexed upon their surfaces which engage said cup 30 portions, while their upper edges are inclined and adapted to contact with the under surfaces of the tread portions of the rails. In this modification an insulation-strip 15 is shown of a single piece and entirely surrounding the flanges and webs of the rails adjacent to their meeting ends and the insulation-sleeves 16, which receive the bolts 5, are shown as extending through the web portions of the chair and also the insulation-strip 35 15, bearing against the opposite faces of the web of the rail, while bars, preferably of a wood fiber 17, are held in contact with the outer faces of the web portions of the chair by means of the nuts and heads of the bolts and 40 flanged portion of said sleeve. In Fig. 5 of the drawings the construction of the web portions of the chair slightly differentiate from the form shown in Figs. 3 and 4 in that the upper parts of the webs of the chair are 45 somewhat thicker, and instead of the web being bent as shown in Fig. 4 recesses are formed for the reception of the insulation-strips 14.

50 Referring to Figs. 6, 7, and 8 will be seen a still different modified form of my invention in which instead of having the chair made of a single piece of metal I form the same in two parts, (designated by numerals 18 and 19,) the former of which has one end 55 20 cupped, as shown in the other figures, for the reception of the insulation-strips 14 and bends about the flanges and bottoms of the rails and has the insulation intermediate the same and the rails. A portion of section 18 of the chair is bent at right angles adjacent to 60 65 corresponding edges of the flanges of the

rails and at the upper edge of the vertical portion thereof is turned to form a roll 21, designed to engage over a rib 22, formed upon the outer edge of the section 19 of the chair, as clearly shown in cross-section in Figs. 7 and 8. Bolts 5 are passed through the insulation-sleeves 16, and the assembled parts of the apparatus are held securely clamped together by means of nuts 11 upon the bolts. In Fig. 8 I have shown a slightly-modified form of bar 75 23, which instead of being solid, as shown in Fig. 7, is formed of a resilient metal which is bent upon itself forming two resilient wings, which are adapted to yield slightly and designed to hold the upright portions of the 80 chair-sections in clamping relation.

In Fig. 9 I have shown a cross-sectional view illustrating a still different modification of my invention, in which one of the chair-sections 19 is bent upon itself and combining 85 with the piece the parts which are illustrated in Fig. 8 as being made of two parts, and the upright portions of the chair-section are provided with registering apertures through which the bolt 5 passes and held by the bolt 90 and nut thereon in clamping relation against the insulation which contacts with the web of the rail.

95 From the foregoing it will be noted that by the provision of the apparatus shown and described means are afforded for thoroughly insulating rails of a railway from metallic fish-plates or chairs supporting the rails, also insulation means being afforded for the adjacent ends of the rails where they are supported in a common chair. By the provision of the means shown parts of the insulating means at the ends of the rails which are subjected to the most wear incident to the heavy strain of the pounding action of the wheels 100 passing over the ends of the rails may be 105 easily removed and replaced without disturbing the joints or rails.

100 What I claim is—

110 1. An insulated rail-joint, comprising in combination with railway-rails, a rail-chair surrounding the flanges and webs of the rails adjacent to their meeting ends, an insulating material intermediate the chair and the rails, removable insulating-strips held by the upright portions of said chair from contact with the webs of the rails against the under edges of the treads of the rails, and insulated means for holding the parts assembled, as set forth. 115

120 2. An insulated rail-joint, comprising in combination with railway-rails, a rail-chair surrounding the flanges and webs of the rails adjacent to their meeting ends, an insulating material intermediate the chair and the rails, the upper edges of the webs of said chair being cupped, removable insulating-strips inserted in the cup portions of the chair and held thereby against the under edges of the treads of the rails, and insulated means for holding the parts assembled, as set forth. 125 130

3. An insulated rail-joint, comprising in combination with rails, a chair surrounding the flanges and webs of the rails adjacent to their ends, insulating material intermediate the rails and chair, removable insulating-strips supported by the webs of the chair and held in contact with the under edges of the treads of the rails, yielding bars held in contact with the outer faces of the web portions of said chair and insulated fastening means passing through the registering apertures in said bars and webs of the rail and chair, as set forth. 55
4. An insulated rail-joint, comprising in combination with rails, a chair surrounding the flanges and webs of the rails adjacent to their ends, insulating material intermediate the rails and chair, removable insulating-strips supported by the webs of the chair and held in contact with the under edges of the treads of the rails, yielding bars formed of metal bent upon themselves and held against the outer faces of the webs of the chair and insulated bolts passing through registering apertures in said bars and webs of the rails and chair and insulated nuts upon said bolts, as set forth. 60
5. An insulated rail-joint, comprising in combination with rails, a chair made up of two sections which surround the flanges and webs of the rails adjacent to their meeting ends, insulating material between the chair-sections and the flanges of the rails, one of said chair-sections having an upright portion 30 designed to interlock with the lower longitudinal edge of the other section, removable insulating-strips separate from the insulation between the chair-sections and flanges, and supported by the upper ends of the chair-sections and held in contact with the under edges of the treads of the rails and insulated means for holding the parts assembled, as set forth. 75
6. An insulated rail-joint, comprising in combination with rails, a chair made up of two sections which surround the flanges and webs of the rails adjacent to their meeting 45 ends, one of said chair-sections having an upright portion 35 designed to interlock with the lower longitudinal edge of the other section, removable insulating-strips supported by the upper ends of the chair-sections and held in contact with the under edges of the treads of the rails, yielding metallic bars held in contact with the outer faces of the chair-sections and insulated means for holding the parts assembled, as set forth. 80
7. An insulated rail-joint, comprising in combination with rails, a chair made up of two sections which surround the flanges and webs of the rails adjacent to their meeting ends, one of said chair-sections having an upright portion 40 designed to interlock with the lower longitudinal edge of the other section, removable insulating-strips supported by the upper ends of the chair-sections and held in contact with the under edges of the treads of the rails, yielding metallic bars held in contact with the outer faces of the chair-sections and insulated means for holding the parts assembled, as set forth. 85
8. An insulated rail-joint, comprising in combination with rails, a chair surrounding the flanges and webs of the rails adjacent to their meeting ends, insulating material intermediate the chair and rails, the upper ends of the webs of said chair being outwardly turned, removable insulating-strips held by said web portion of said chair against the under edges of the treads of the rails, bars held in the recesses formed by the outwardly-bent 45 portions of said chair and insulated fastening means passing through said bars and webs of the rails and chair, as set forth.

In testimony whereof I affix my signature in presence of two witnesses.
